(57) **CLAIM**

The ornamental design for a pet treat, substantially as shown and described.

DESCRIPTION

FIG. 1 is a front perspective view of a first embodiment of a pet treat showing my new design;

FIG. 2 is a top view of the design of FIG. 1;

FIG. 3 is a bottom view of the design of FIG. 1;

FIG. 4 is a left side elevational view of the design of FIG. 1;

FIG. 5 is a right side elevational view of the design of FIG. 1;

FIG. 6 is a front elevational view of the design of FIG. 1;

FIG. 7 is a rear elevational view of the design of FIG. 1;

FIG. 8 is a front perspective view of a second embodiment of the pet treat showing my new design;

FIG. 9 is a top view of the design of FIG. 8;

FIG. 10 is a bottom view of the design of FIG. 8;

FIG. 11 is a left side elevational view of the design of FIG. 8;

FIG. 12 is a right side elevational view of the design of FIG. 8;

FIG. 13 is a front elevational view of the design of FIG. 8;

FIG. 14 is a rear elevational view of the design of FIG. 8;

FIG. 15 is a front perspective view of a third embodiment of the pet treat showing my new design;

FIG. 16 is a top view of the design of FIG. 15;

FIG. 17 is a bottom view of the design of FIG. 15;

FIG. 18 is a left side elevational view of the design of FIG. 15;

FIG. 19 is a right side elevational view of the design of FIG. 15;

FIG. 20 is a front elevational view of the design of FIG. 15;

and,

FIG. 21 is a rear elevational view of the design of FIG. 15.
